CLAIM

The ornamental design for a toy snake, as shown and described.

DESCRIPTION

FIG. 1 is a top plan view of a toy snake of the present invention, the broken lines illustrating the toy snake in use;

FIG. 2 is left side elevation view of the toy snake shown in FIG. 1, the right side of the toy snake being a mirror image thereof;

FIG. 3 is a bottom plan view of the toy snake shown in FIG. 1;

FIG. 4 is a rear elevation view of the toy snake shown in FIG. 1; and,

FIG. 5 is a front elevation view of the toy snake shown in FIG. 1.

The phantom, broken lines shown in the drawings form part of the design that is not claimed herein.
